ALBERT DREYER, OF LUCERNE, SWITZERLAND

MACHINE FOR MAKING HIGHLY ELASTIC RESILIENT TUBES

Application filed February 19, 1931, Serial No. 517,129, and in Germany December 20, 1930.

This invention relates to a machine for making highly elastic resilient tubes, or so-called bellows, such as are used as constructional elements for thermostats, pressure controlling apparatus, stuffing boxes and the like.

The new feature of the subject matter of the invention, as distinguished from well known devices of similar kind which operate either incorrectly or are very expensive, essentially is that inner permanently rotating pressure rollers automatically adapt themselves to the cam-like peripheral rib, decreasing in width and increasing in depth, of an outer intermittently rotating pressure roller, whereby the corrugations of the resilient tube are formed positively. The profile decreasing in width and increasing in depth of the outer pressure roller suitably comprises only about four-fifths of the periphery of said roller, while the rest of the periphery has a profile of uniform small thickness and uniform height, so that the resilient tube to be made is compelled to make at least one complete revolution while running over this section of the roller.

By using a machine according to the invention not only the expenses of production of resilient tubes are lowered but also the quality of such tubes is remarkably improved because in consequence of a most uniform distribution of the material it is not subject to overstraining.

By means of the machine constructed according to the invention not only preliminarily corrugated but also smooth tubes may be used for converting them into resilient tubes. The use of preliminarily corrugated tubes instead of smooth tubes has the advantage of a better distribution of the material.

The preliminary corrugation of the tubes may be effected in any well known manner. For this purpose it is particularly advisable to use a caoutchouc die which by means of a displaceable metallic plunger is pressed against a stationary metallic support and thereby compressed so that by the radial expansion of said caoutchouc die that part of the wall which covers the annular grooves of the matrix is formed into corrugations. The preliminary corrugation of the tube may also be

effected in any other way, for instance, by rolling, or by hydraulic pressure.

In the case that corrugated tubes are to be produced having a bottom it is advisable, when using smooth tubes, to begin at the bottom in making the corrugations, so as to obtain corrugated resilient tubes in which the distances between the bottom and the first corrugation are equal. When resilient tubes of this kind are made which are open at both ends the production of the corrugation may be begun at either end or at any part between these ends.

A further feature of the invention resides in the fact that the new method according to the invention allows of using a relatively short and stiff inner rolling spindle because the resilient tube is made in one continuous process so that, in the case of resilient tubes having a bottom, the rolling spindle needs only to have a length which is equal to that of said tube, while in the case of making resilient tubes which are open at both ends, the rolling spindle has only one half of the length of said tube. In well known processes for rolling corrugated resilient tubes, the longitudinal contraction of the originally long tube is effected successively in several stages so that, for the first stages of rolling, where the tube is still long, relatively long rolling spindles must be used which, of course, are not so stiff and rigid as the spindles used when using the machine according to the present invention.

In the accompanying drawings there is shown for purposes of illustration only, and in more or less diagrammatic manner, a preferred embodiment of the present invention, it being understood that the drawings do not define the limits of the present invention as changes in the construction and operation disclosed therein may be made without departing either from the spirit of the present invention or the scope of the broader claims. In the drawings:

Fig. 1 is a plan view of the machine, 95
Fig. 2 an end view of the same,

Fig. 3 a longitudinal sectional view on the line 3—3 of Fig. 1 on an enlarged scale,

Figs. 4 and 5, 6 and 7 are detail views showing the working positions of the tools 100

when operating on preliminarily corrugated and on smooth tubes.

Referring to Figs. 1-3 of the drawings 1 indicates the head-stock and 2 (Figs. 1 and 2) a 5 roller supporting plate, preferably carried by feet of cast-iron 3.

The head-stock 1 is provided with two bearings 4 and 4¹ which receive the spindles 5 and 6, of which the spindle 5 is slideable in the 10 spindle 6, so as to allow of a relatively reciprocal longitudinal displacement of the two spindles. On that end of the spindle 5 which projects from the bearing 4 is fastened a pulley 7 rotated by a belt driven by an intermediate 15 gearing which is provided with coupling and uncoupling means. The pulley is preferably provided with a transversely curved rim for the purpose of compelling the belt to run always in the plane of symmetry 20 of the pulley in whatever displaced position said pulley may be.

A groove 8 (Fig. 3) serves for the reception of a tongue 9, which has for its purpose to transmit the rotation of the spindle 5 to the 25 spindle 6. At its other end the spindle 5 is provided with female thread 10 into which the inner rolling spindle 11 may be screwed. The spindle 6, at its end lying outside the bearing 4¹, is provided with a chuck 12 serving 30 for the reception of an intermediate centering lining 13, which is screwed into said chuck. A nut-lock 14 having the form of a collar serves for locking the centering lining 13. For this purpose the nut-lock 14 has a 35 gap 15 which by means of a screw 16 may be narrowed so as to lock the nut-lock 14 and prevent its displacement during the operation of the machine. The centering lining 13 is provided with female thread into which the 40 outer rolling spindle 17 is screwed. Said spindle 17 possesses a polygonal collar 18 for tightening or loosening the rolling-spindle 17 by means of a fork-wrench. The centering lining 13 may be made in one piece with the 45 outer rolling spindle 17, 18. By screwing the lining 13 or the spindle 17 more or less into the chuck 12, the distance between the two pressure-rollers 19, 20 may be adjusted. This distance of the two inner pressure-rollers 50 depends on the required height of the corrugations or on the distance of the preliminary corrugations of the preliminarily corrugated resilient tube. The rollers 19 and 20 are so adjusted, that they fit as exactly as possible 55 into the preliminarily rolled inner grooves 21 of the tube 22, as represented in Fig. 4.

For the purpose of enabling the spindles 5 and 6 to be longitudinally displaced during 60 their rotation they are provided with bronze-bushes 23 and 24 (Fig. 3.) These bushes are rotatable between end-bearings 25, 25¹ and 26, 26¹ respectively.

A lateral displacement of the bronze-bushes 65 on the spindles is prevented by col-

lars 27, 28 and by adjusting rings 29, 30, ring 29 being screwed on the spindle 5 and ring 30 on the spindle 6. The rings 29 and 30 are fixed in their respective positions by screws 31 and 32 respectively.

The lateral displacement of the bronze-bushes 23 and 24 and, therefore, of the spindles 5 and 6 is effected by fork-levers 33 and 34 (Fig. 1) the prongs of which embrace the bushes 23 and 24 by the bell-shaped parts 35 and 36 respectively. Said bell-shaped parts by means of screw-plugs 37, 37¹ and 38, 38¹ respectively are pivotally connected with the said bronze-bushes. The rear ends of the prongs of the fork-levers 33 and 34 are rotatably fastened to the pillars 39, 40 respectively mounted on the base plate of the head-stock 1. At their other ends the fork-levers 33 are connected by links 42, 43, 44. The link 42 with its centre is pivotally mounted on a pillar 41 which is fastened to the base-plate of the head-stock 1. This link 42 by means of the intermediate links 43 and 44 and the screw-plugs 45, 46, 47 and 48 is pivotally connected to the fork levers.

The lever 42 has an extension 49 which is engaged by a draw-spring 50. The said extension 49 is provided with a number of holes 51 into each of which the end of the spring 50 may be hooked so that the leverage 55 may be changed according to circumstances.

The other end of the spring 50 is fastened to a plug 52 mounted on the base-plate 2 and eventually capable of being adjusted.

Pivotally mounted on the plug 47 is a part 53 the free end of which forms a threaded bolt 56. On a screw-plug 61 a part 54 is pivotally mounted the free end of which forms a threaded bolt 57. One of these threaded bolts or screws has right-handed thread and the other one left-handed thread. A nut 58 one half of which is provided with right-handed inner thread and the other half of which is provided with left-handed inner thread is screwed on the threaded bolts or screws 56 and 57. According to the direction in which the nut is turned the distance between the plugs 47 and 61 is increased or decreased.

The plug 61 is fastened to a lever 62, which is pivoted on a plug 63¹ fastened to the plate 2. The free end of said lever 62 is provided with a handle 63. On the base-plate 2 are mounted ball-bearings 64, 65 which carry the 120 axle 66.

The axle 66 carries a collar 68 against which the pressure-roller 67 is firmly pressed by means of a nut 69 for the purpose of rigidly connecting the said pressure roller to the said axle.

The pressure-roller 67 at its periphery is provided with a cam-like rib or ring 70 having a cross-section decreasing in width and increasing in height. For producing one 130

corrugation the pressure-roller or disc 67 makes only one revolution, and for this purpose it begins with the broad low portion of the profile fitting into the preliminary corrugation of a preliminarily corrugated tube 22 (Fig. 4), and ends with the high narrow portion of the profile (Fig. 5).

If a tube 22¹ having a smooth wall (Figs. 6 and 7) is to be corrugated the low broad profile of the cam-like rib 70 at the beginning of the revolution of the roller or disc 67 lies close to the outside of the tube 22¹ (Fig. 6).

At that point where the broad profile of the ring 70 begins and the narrow profile terminates is arranged a recess 71 (Fig. 2).

The disc shaped roller 67 at the moment when the recess 71 is situated between the two pressure-rollers 19, 20 (Fig. 2) is arrested by a stop 72 (Fig. 1) engaging a hole 73 of the roller 67 in which position the corrugation operated upon is finished (Figs. 5 and 7). After finishing each corrugation the tube 22 or 22¹ is released.

The decreasing profile of the disc shaped roller 67 extends only to about four-fifths of the periphery of said roller while the remaining one fifth of the periphery of said roller shows a uniformly thin profile, the length of which is at least equal to the inner diameter of the finished corrugation so that the resilient tube makes at least one complete revolution while it is operated upon by said thin portion of the profile whereby all corrugations are made uniform.

The stop 72 (Fig. 1) is situated in a sleeve 74 and, by means of a spring arranged in said sleeve is pressed against the roller 67. The other end of the stop 72 has a perpendicularly bent projection 76 which engages a slot 75 of the lever 62.

The adjusting screw 77 allows of an exact adjustment of the base plate 2 and of the disc-shaped roller 67 in relation to the inner rollers 19, 20.

The corrugating device operates as follows: The spindles 5 and 6 and consequently the inner rollers 19, 20 rotate continuously. Then the operator with his right hand takes the tube 22 (or 22¹) and brings it into a position which is as nearly as possible parallel to the spindle of the head stock. His left hand seizes the handle 63. The disc shaped roller is in its initial position, as shown in Fig. 2, so that the tube may be pushed on the rotating rollers 19, 20 and the first depression which is to be formed between the two waves lies between the said rollers 19, 20 (Figs. 4 and 6). Now the operator turns the handle 63 to the left in the direction of the arrow I (Fig. 1) whereby the two inner rollers 19, 20 by means of the levers 33 and 34 and the links 42, 43 and 44 are moved apart symmetrically. The handle 63 having reached its end position and the stop 72 being thereby uncoupled

from the disc-shaped roller 67 the last is released. On account of the fact that the broader portion of the profile 70 of the roller 67 is heavier than the lower thin portion of the profile and that due to the ball bearing 70 the resistance to be overcome is only weak the roller 67 will at once begin its rotation and is further driven by the rotating discs 19, 20 and the tube 22.

In the moment the disc shaped roller 67 comes between the rollers 19, 20, the handle 63 is released so as to return to its initial position. The spring 50 at the same time pushes the lever 49 back and presses thereby both rollers 19, 20 towards each other thereby exercising a pressure on both flanks of the corrugation being formed. In this way the flanks of the corrugations are strongly pressed against the rib 70 of the disc shaped roller 67 thereby avoiding the formation of 85 folds and facilitating the formation of the corrugations and effecting perfectly smooth corrugations.

As soon as the roller 67 has made a complete revolution, the lever 62 will be returned to its initial position, and the stop 72 engages again the hole 73 of the disc 67 whereby this disc is stopped. The operator displaces now the tube 22 a distance equal to the width of one corrugation and operates again the handle 63 as before described so that the parts are again in the position shown in Figs. 4 and 6.

The manufacture of each corrugation takes only a few seconds. It is, for instance, possible to make 40 resilient tubes per hour of about 26 millimeters inner diameter and 38 millimeters outer diameter and having each 30 corrugations. These 1200 corrugations require only $\frac{1}{4}$ H. P. The tube corrugating 105 machine according to the present invention in contradistinction to known machines of similar kind works extremely economically.

What I claim is:

1. In a machine for making highly elastic 110 resilient tubes having annular corrugations, the combination of pressure rollers working inside the tube to be furnished with corrugations, a roller working outside said tube, a cam-like rib arranged at the periphery of said roller and provided with a transverse recess in its peripheral surface for cooperating with the tube and the rollers at the initial starting of the machine.

2. In a machine for making highly elastic 120 resilient tubes having annular corrugations, the combination of relatively movable pressure rollers working inside the tube to be furnished with corrugations, a roller working outside said tube, a cam-like rib arranged at the periphery of said roller and provided with a transverse recess in its peripheral surface, and the cross-section of said rib beginning from said recess decreasing in width and increasing in height. 125

3. In a machine for making highly elastic resilient tubes having annular corrugations, the combination of two rollers working inside the tube to be furnished with corrugations, a spindle to which one of said rollers is fastened, a hollow spindle to which the other roller is fastened and in which the said first spindle is axially arranged and a coupling arranged between said spindles and allowing of their reciprocal axial adjustment and compelling them to turn jointly.
4. In a machine for making highly elastic resilient tubes having annular corrugations, the combination of an inner spindle carrying one of two rollers and an outer spindle carrying the other one of said two rollers, and a pulley fastened to the inner spindle, and a coupling arranged between said spindles and allowing of their reciprocal axial adjustment and compelling them to turn jointly.
5. In a machine for making highly elastic resilient tubes having annular corrugations, the combination of two reciprocally adjustable and rotatable roller carrying spindles, a coupling arranged between said spindles and allowing of their reciprocal axial adjustment and compelling them to turn jointly, and two levers, one being pivotally connected with one of said spindles and the other one being pivotally connected with the other spindle.
6. In a machine for making highly elastic resilient tubes having annular corrugations, the combination of two rollers, two reciprocally adjustable and rotatable spindles each carrying one of the rollers, a coupling arranged between said spindles and allowing of their reciprocal axial adjustment and compelling them to turn jointly, and two levers, one being pivotally connected with one of said spindles and the other one being pivotally connected with the other spindle, and connecting links between said levers.
7. In a machine for making highly elastic resilient tubes having annular corrugations the combination of two reciprocally adjustable and rotatable roller carrying spindles, and two levers, one being pivotally connected with one of said spindles and the other one being pivotally connected with the other spindle, connecting links between said levers, an extension on one of said links, a lever, means for adjustably connecting said extension with said lever, a spring acting on the extension, a stop connected with said lever, and a rotatably mounted disc shaped roller cooperating with the roller carrying spindles and provided with a hole for cooperating with the stop.

In testimony whereof I affix my signature.
ALBERT DREYER.
